UNITED STATES PATENT OFFICE.

HAROLD BREADY WEAVER, OF NEW YORK, N. Y., ASSIGNOR TO AMERICAN MOTORBUS CORPORATION, A CORPORATION OF NEW YORK.

DESIGN FOR A MOTOR-BUS BODY.

51,740.

Specification for Design.

Patented Feb. 5, 1918.

Application filed July 24, 1917. Serial No. 182,555. Term of patent 7 years.

To all whom it may concern:

Be it known that I, HAROLD B. WEAVER, a citizen of the United States, residing at New York, in the county of New York and State of New York, have invented a new, original, and ornamental Design for Motor-Bus Bodies, of which the following is a specification, reference being had to the accompanying drawings, forming part thereof.

The design is shown in the accompanying drawings, in which—

Figure 1 is a side view;
Fig. 2 is a rear view of the automobile body; and
Fig. 3 is a front view of the same.
I claim:
The ornamental design for a motorbus body as shown.

HAROLD BREADY WEAVER.
